UNITED STATES PATENT OFFICE

1,987,139

INTERIOR AWNING ADJUSTER

Edward T. Boyd, Houston, Tex.

Application February 24, 1930, Serial No. 430,768
Renewed December 7, 1931

7 Claims. (Cl. 156—15)

The invention relates to an insert or adjuster for cords or strands of material which pass through a wall or frame.

In building construction it is usual to have the window and door screens and frames within a casing and when awnings are employed they are mounted outside of this casing. In order to manipulate the awning, however, it is necessary to open the window and the screen in order to obtain access to the awning cords. This procedure is more or less clumsy and awkward and it is with the idea of providing a simple and economical construction whereby the awning may be manipulated that I have devised the present invention.

It is one of the objects of the invention to provide a simple and economical article which may be used to retain the awning cords and permit their adjustment.

Another object of the invention is to provide an insert for the window or screen frame which will permit the extension of strands of material therethrough.

A still further object of the invention is to devise an insert which will fit diagonally into the frame so that the awning cords may pass therethrough with the least amount of friction.

A still further object of the invention is to provide an adjuster having a plurality of lugs which will permit fastening of the cords in any desired position.

The invention will be readily understood by having reference to the drawing wherein

Fig. 1 is a perspective view of one form of the invention.

Fig. 2 is a sectional view taken through a window construction and disclosing the invention applied to a screen and awning.

Fig. 3 is a sectional view taken on the line 5—5 of Fig. 1.

The numeral 2 indicates a casing such as is generally used in building construction. This casing usually supports the window sash as well as the screen frame 3. Inside of the screen 3, and not shown, is the usual window. The frame 3 comprises the upper cross member 4 and the lower cross member 5, which are connected by means of stiles 6. The screen fabric 7 is held in position by means of the frame 3. An awning of ordinary construction is illustrated at 10 and is adapted to be raised and lowered in the customary manner. To accomplish this movement cords 11 are provided, which are connected to the frame of the awning at 12. It is usual to have two of the cords 11, one connected to each of the outer

corners of the awning. These cords pass upwardly and over a pulley 13. Ordinarily the cords from the pulley 13 pass downwardly and are engaged about a block or anchor, which is fastened to the casing 2. With such construction, however, the anchor for the cords is outside of the screen frame 3 and is inaccessible from the interior of the building. It is, therefore, necessary to remove the screen as well as to open the window in order to manipulate the awning, and it is with the idea of avoiding this operation that I have devised my invention.

The insert is best seen in perspective view in Fig. 1 and comprises a body 15, with a face plate 16 connected to one end thereof. It should be particularly noted that the body 15 extends angularly away from the face plate 16. In this manner, by cutting an opening in one or both of the stiles 6 of the screen the body 15 may be inserted therein. It seems apparent that the angular displacement of the body with respect to the face plate 16 may be constructed as desired. It is intended that when the body 15 is inserted in the opening of the frame that the face plate 6 will abut against the flat surface of the frame or stile 6.

Suitable openings 17 are provided to receive attaching means so that the insert or adjuster will be firmly held in position. In the embodiment here illustrated I have shown a plurality of passages 20 extending through both the face plate and the body. These passages are adapted to receive the cords from the awning and are of such size that the cords will slip freely therein.

Directly below the passages 20 in the face plate 16 I have provided a plurality of lugs 21. These lugs are so arranged that a slot 22 is provided directly beneath each of the passages. This slot 22 is tapered so that it has a lesser width at its lower side than at the upper side and a lesser width adjacent the plate so that it tapers downwardly and inwardly. In this manner when the cord is extended through the passage 20 it may be drawn down to the position shown in Fig. 2, and frictionally engaged in the slot 22. This will prevent movement of the cord until it is moved away from the wedge or V-shaped slot.

With the construction just described it seems apparent that the device will be simple to install as it is merely necessary to form an opening in the frame and insert the body member so that it may be suitably fastened by means of tacks or screws passed through the openings 17. The awning cords may then be extended through the passages 20 and engaged in the slots 22 so

that any subsequent manipulation of the awning may be accomplished from the interior of the building without removing the screen.

While I have shown and described the invention as applied to an awning and a screen it seems apparent that the construction may also be applied to the window sash and when it is desired to move the sash up and down it will only be necessary to release the cords from the grooves 22 so that they may slide freely through the passages 20. It also seems apparent that the insert may be used in the lower portion of the screen or the window sash to permit the passage of wires such as are used in connection with radio receiving sets. It is also intended that the invention may be applied to both the window and the screen in the same construction if desired. While I have shown one particular embodiment which the invention may assume it seems apparent that the size and shape of the device may be varied in accordance with circumstances encountered.

What I claim as new and desire to protect by Letters Patent is:

- 25 1. An awning cord adjuster comprising a body adapted for insertion in a window screen frame and to have the awning cord pass therethrough, means whereby said adjuster may be fastened to the frame, and means on said adjuster to releasably retain the awning cord comprising a tapered slot into which the cord is to be wedged.
- 30 2. An awning cord adjuster including, a face plate, a plurality of passages through said plate and means in said plate to frictionally retain awning cords which extend through said passages including spaced lugs forming a downwardly inwardly tapering slot.

3. A device of the character described including a body portion, a face plate thereon, a plurality of lugs on said plate, and inwardly tapering slots between said lugs whereby cords extending through said slots may be frictionally restrained from outward movement.

4. An awning cord adjuster block formed for insertion in a screen frame, said block including a face plate, a body extending diagonally from said plate, slots through said body and plate for the awning cords whereby they may extend to the inside of the window screen, and stationary means on said block to receive said cords to retain the awnings in any desired position of adjustment.

5. An awning cord adjuster insert for frames including means to receive the awning cords, fixed means also on said adjuster to retain the awning cords in any adjusted position, and means whereby said insert may be attached to the frame.

6. An awning cord holder for screens including a portion adapted for attachment to the screen, a portion adapted to have the awning cords passed therethrough, and a portion into which the cord may be wedged to frictionally hold the cord in any adjusted position, said last portion including spaced lugs to form a tapered slot.

7. An awning adjuster for use on windows to which a screen is applied including a plate for the screen frame, means in said plate for the passage of the awning cords, and stationary means fixed on said plate to releasably retain the awning cords, said means including a tapered slot into which the cord may be wedged.

EDWARD T. BOYD.
